ROTOR-SHAFT CONNECTION

Warren Doble, North Hollywood, Calif., assignor to
Jabsco Pump Company, Burbank, Calif., a corporation
of California

Application September 3, 1957, Serial No. 681,797

3 Claims. (Cl. 287—52)

The present invention relates to means for transmitting rotation between a shaft and a rotor telescoped over the shaft, a primary object of the invention being to provide a torque-transmitting rotor-shaft connection which effectively prevents relative movement between the rotor and the shaft during rotation thereof so as to minimize wear, but which at the same time provides for a loose fit between the rotor and the shaft so that the rotor may be installed and removed readily without the use of any special tools or equipment.

The invention is of particular utility as applied to a pump having an elastomeric impeller provided with flexible radial vanes, and is for the purpose of transmitting rotation of the shaft of the pump to a rotor having the form of an insert molded into and bonded to the elastomeric impeller. The impeller of a pump of this type must be replaced periodically and it is desirable, and frequently essential, that such replacement be capable of being performed manually. For example, a pump of the nature under consideration may be used as the bilge pump of a boat and ease of impeller replacement in this instance may well be a matter of life or death. The present invention provides for such easy impeller replacement by making the fit between the impeller insert and the pump shaft loose enough that the impeller may be removed and installed manually.

In order to prevent excessive wear of the shaft and/or the impeller insert due to the loose fit therebetween, the invention provides means for effectively locking the impeller insert and the shaft together during rotation of the shaft, such means operating in response to a slight initial rotation of the shaft relative to the impeller insert, which is an important feature of the invention.

An important object of the invention is to provide a torque-transmitting connection between the impeller insert and the shaft which produces engagement between the insert and the shaft at three circumferentially spaced points in response to a slight initial rotation of the shaft relative to the insert upon starting of the pump. This provides a stable three-point contact between the insert and the shaft and insures that there is always a force component available to oppose the side load resulting from the flexure of the vanes of the impeller and resulting from the pumping load.

Another object of the invention is to provide a torque-transmitting connection between the impeller insert and the pump shaft which centers the impeller on the shaft in response to a slight initial rotation of the shaft relative to the impeller.

The foregoing results are achieved in accordance with the present invention by providing the shaft with two substantially diametrically opposite, longitudinally extending, flat-forming chordal walls and by providing the impeller insert with an internal key which is engageable with one of the flats at a point spaced from the circumferential center thereof, the longitudinal edges of the other of the walls being brought into engagement with the interior of the impeller insert upon a slight initial

2

rotation of the shaft relative to the insert, it being an important object of the invention to provide a torque-transmitting connection of this nature.

The foregoing objects, advantages, features and results 5 of the present invention, together with various other objects, advantages, features and results thereof which will be apparent to those skilled in this art in the light of the present disclosure, may be attained with the exemplary embodiment of the invention described in detail hereinafter and illustrated in the accompanying drawing, in which:

Fig. 1 is a longitudinal sectional view of a pump which embodies the invention;

Fig. 2 is a transverse sectional view of the pump which 15 is taken as indicated by the arrowed line 2—2 of Fig. 1; and

Fig. 3 is a fragmentary transverse sectional view duplicating a portion of Fig. 2 and illustrating the operation 20 of the invention.

Referring to the drawing, the numeral 10 designates a pump having a housing 12 which is provided with an impeller bore 14 and which is provided with inlet and outlet ports 16 and 18 in communication with the impeller bore. Disposed within the impeller bore 14 at 25 one side thereof and between the inlet and outlet ports 16 and 18 is a cam 20, the cam being shown as secured to the housing 12 by a screw 22. The inner surface of the cam cooperates with the peripheral wall of the impeller bore 14 to provide an impeller chamber 30 designated generally by the numeral 24, the inner surface of the cam providing the impeller chamber with a minimum radius between the inlet and outlet ports.

Extending longitudinally into the impeller chamber 24 and coaxial with the impeller bore 14 is a shaft 26, 35 shown as the shaft of an electric motor 28 the housing of which is connected to the pump housing 12 by a structure 30. The shaft 26 has telescoped thereover a generally cylindrical impeller insert 32, there being a torque-transmitting connection 34 between the shaft 26 40 and the insert 32 which will be described hereinafter. Molded onto and bonded to the impeller insert 32 is an elastomeric impeller 36 having flexible radial vanes 38 which alternately engage the peripheral wall of the impeller bore 14 and the inner surface of the cam 20 as 45 the impeller 36 is rotated within the impeller chamber 24 by the shaft 26.

As will be apparent, the cam 20 flexes the vanes inwardly in the vicinity of the outlet port 18 to decrease 50 the volumes of the intervane spaces adjacent the outlet port, thereby discharging fluid from the intervane spaces into the outlet port. As the vanes 38 disengage the cam 20, which occurs in the vicinity of the inlet port 16, the intervane spaces are increased in volume to draw fluid 55 to be pumped into the intervane spaces from the inlet port. This is the characteristic pumping action of a pump of this type, as is well known in the art.

Considering the torque-transmitting connection 34 of the invention, the shaft 26 is provided with two substantially diametrically opposite, longitudinally extending, 60 nonconvex, chordal walls which form at least substantially parallel flats 40. The impeller insert 32 is provided with an internal key 42 which is engageable with one of the flats 40, at a point spaced circumferentially from the center thereof. In the construction illustrated, the impeller insert is merely a sheet metal tube onto which the impeller 36 is molded and bonded, the key 42 being an inwardly struck dimple.

The diameter of shaft 26 and the inside diameter of 65 the impeller insert 32 are so related that there is sufficient clearance between the shaft and the insert to permit installation of the impeller 36 on and removal thereof from the shaft readily, preferably manually without the

use of any tools. This greatly facilitates replacement of the impeller 36, particularly where it is inconvenient or impossible to use special tools or equipment.

Referring to Fig. 3 of the drawing, when the pump 10 is first started, the shaft 26 rotates relative to the impeller insert 32 through a small angle, which is exaggerated in Fig. 3, such relative rotation occurring as the result of the resistance to rotation offered by the impeller 36. This slight relative rotation between the shaft 26 and the impeller insert 32 results in engagement of the key 42 with one of the flats 40 at a point circumferentially spaced from the center thereof and results in engagement of the longitudinal edges of the other flat 40 with the peripheral wall of the opening through the insert, which centers the impeller on the shaft. While engagement between the interior of the insert 32 and the "longitudinal edges" of one of the flats 40 is referred to herein, in actual practice narrow longitudinal bands of the shaft 26, each bordered on one side by one of the longitudinal edges of such flat, engage the insert.

The foregoing interengagement between the shaft 26 and the impeller insert 32, after a slight initial rotation of the shaft relative to the insert, produces stable three-point contact or engagement between the shaft and the insert, as indicated by the arrows 44. Such three-point contact insures that there is always a force component acting in a direction to resist the side load imposed on the impeller by the cam 20 and by the pumping load.

With the foregoing construction, once the shaft 26 has rotated relative to the impeller insert 32 sufficiently to produce the three-point engagement indicated by the arrows 44, no further relative movement of the shaft and the insert takes place. In other words, even with a side load on the impeller 36 which varies in direction relative to the key 42 as the impeller rotates, the impeller insert 32 will not work back and forth on the shaft 26 as the shaft and the impeller continue to rotate due to the fact that the three-point contact described insures the constant presence of a force component opposing the side load on the impeller. Consequently, wear of the shaft 26 and the impeller insert 32 is minimized, despite the existence of a loose fit permitting easy installation and removal of the impeller.

Thus, the present invention provides a very simple and effective means of achieving easy impeller removal and installation without incurring excessive wear due to the loose fit between the impeller insert 32 and the shaft 26, which is an important feature of the invention.

Although an exemplary embodiment of the invention has been disclosed herein for purposes of illustration, it will be understood that various changes, modifications

and substitutions may be incorporated in the specific embodiment disclosed without departing from the spirit of the invention as defined by the following claims:

1. In combination: a shaft having two substantially diametrically opposite, longitudinally extending, nonconvex walls each having two longitudinal edges and a longitudinal centerline midway between its said longitudinal edges; and a member telescoped over said shaft and having thereon an internal key engaging one of said walls between said longitudinal centerline of said one wall and one of said longitudinal edges of said one wall upon relative rotation of said shaft and said member, said shaft engaging the interior of said member adjacent said longitudinal edges of the other of said walls upon said relative rotation of said shaft and said member.

2. In combination: a shaft having two substantially diametrically opposite, longitudinally extending flats each having two longitudinal edges and a longitudinal centerline midway between its said longitudinal edges; and a member telescoped over said shaft and having thereon an internal key engaging one of said flats between said longitudinal centerline of said one flat and one of said longitudinal edges of said one flat upon relative rotation of said shaft and said member, said shaft engaging the interior of said member adjacent said longitudinal edges of the other of said flats upon said relative rotation of said shaft and said member.

3. In combination: a shaft having two substantially diametrically opposite, longitudinally extending flats each having two longitudinal edges and a longitudinal centerline midway between its said longitudinal edges; and a member having an opening therein which receives said shaft and which is provided with a peripheral wall surrounding said shaft, part of said peripheral wall of said opening being formed by an internal key carried by said member and engaging one of said flats between said longitudinal centerline of said one flat and one of said longitudinal edges of said one flat upon relative rotation of said shaft and said member, longitudinal portions of said shaft adjacent said longitudinal edges of the other of said flats engaging circumferentially spaced longitudinal portions of said peripheral wall of said opening upon relative rotation of said shaft and said member, said longitudinal portions of said peripheral wall of said opening being spaced circumferentially from said key.
